UNITED STATES PATENT OFFICE.

CYRUS HOWARD HAPGOOD, OF NUTLEY, NEW JERSEY, ASSIGNOR TO DE LAVAL SEPARATOR COMPANY, OF NEW YORK, N. Y., A CORPORATION OF NEW JERSEY.

PROCESS FOR SEPARATING SOLIDS FROM LIQUIDS.

Original application filed March 25, 1922, Serial No. 546,810. Divided and this application filed August 3, 1923. Serial No. 655,388.

To all whom it may concern:

Be it known that I, CYRUS HOWARD HAPGOOD, a citizen of the United States, residing at Nutley, county of Essex and State of New Jersey, have invented a new and useful Improvement in Processes for Separating Solids from Liquids, of which the following is a full, clear, and exact description, reference being had to the accompanying drawings, which form a part of this specification.

It is known to effect the separation of two ingredients in solution by reducing the temperature until one ingredient is so far solidified as to throw it out of solution and then to separate the ingredients by filtration, settlement or centrifugal force. Examples of such processes are the separation of amorphous wax (petrolatum) from cylinder oil stock, the separation of crystalline wax (paraffine) from wax distillates, and the separation of stearin from oleo.

The most rapid, efficient, and economical method of separation is by centrifugation, but in certain processes the solidified ingredient does not readily discharge from the bowl but builds up more or less on the periphery of the bowl. Little difficulty in this respect is encountered in the separation of petrolatum from cylinder stock; but in the separation of paraffin wax from wax distillates, it is necessary to blend naphtha with the distillate. The wax will then discharge from the bowl, but each separated ingredient carries out with it a large proportion of naphtha and both ingredients must be distilled to drive off the naphtha. This deterioriously affects the color of the treated material, which must be subsequently filtered to decolorize.

In the separation of stearin from oleo, if the solution is subjected to a temperature sufficiently low to throw the stearin, in a crystallized condition, out of solution, the stearin can be made to discharge from the bowl if there is also introduced into the bowl a heavy cushioning liquid. (e. g., water) which, in its discharge, carries with it the crystallized stearin.

In a joint application filed September 8, 1921, by Selden H. Hall and the present

inventor, Serial No. 499,325, is set forth a process of centrifuging refrigerated mixtures of the above character, and specifically a process of centrifuging wax distillates without dilution or blending with naphtha, which comprises feeding a liquid heavier than either of the ingredients to the periphery of the bowl so as to form a surrounding envelope of heavy liquid, and maintaining such heavy liquid at a temperature sufficient to melt the outer layer of solids while not sufficient to melt the inner layer of solids, thereby allowing the melted portion of the heavier ingredient to readily discharge from the bowl. This process I deem a substantial advance in the art, as it is not only operative but efficient; but the specific manner of execution of the process set forth in said application requires the exercise of a fairly high degree of care and skill, the necessity for which is a factor obstructing the commercial success of the process.

The object of the present invention is to so improve the said Hall and Hapgood process that the liquefaction of the solids adjacent the periphery of the mass of ingredients undergoing centrifugal separation and the discharge of the so liquefied heavier ingredient may be effected without the exercise on the part of the operator of any substantial degree of skill or more than ordinary care.

In the accompanying drawing, the figure is a view of a part of a centrifugal bowl shown partly in elevation and broken away to show the remainder in vertical section and in which my improved process is adapted to be carried out.

The bowl shell *b* is driven from the driving and supporting spindle *a*. The bowl top *c* is removably secured to the shell by the flanged ring *d*. The bowl top *c* has an inwardly extending annular flange *e* at its upper end. This flange is threaded to receive a removable necked weir *f*.

Within the bowl is a "liner" *g* comprising a series of frusto-conical "discs." Above the liner is a top disc *h*, which, at its upper end, has a neck *i* forming a weir within, spaced from, and concentric to, and extending above, the weir *f*, and without, and

concentric to, and spaced from, the feed tube *j*.

Within the bowl and adjacent its inner wall is a heat radiator having a smooth inner surface concentric with the axis of the bowl. The radiator is preferably an annular chamber within which a heating fluid is adapted to circulate. As shown, this chamber is formed from an annulus of sheet metal *k*, the upper part of which is cone-shaped to correspond to the taper of the bowl top and the lower part of which is bent outward and upward. The upper edge of the sheet *k* is flanged *m* and secured to the inwardly extending annular flange *e* of the bowl top. The opposite edge of the sheet *k* is flanged at *n* and secured to the lower part of the bowl top. Thereby is formed an enclosed chamber or compartment *l* extending entirely around the inside wall of the bowl.

The flange *e* of the bowl top is provided with an orifice *o* for admission of a heating liquid. The bowl top, just beneath the flange *e*, is provided with another orifice *p* for discharge of said liquid. Any suitable means may be provided to insure a circulation of the liquid through the chamber from the inlet *o* to the outlet *p*, as, for example, a pipe *r* extending from the orifice *o* downward to near the bottom of the chamber.

Any desired number of orifices *o* and pipes *r* may be provided.

The inwardly flanged part *e* of the bowl top is provided on its top with a circular ledge *s*, forming a receptacle to receive the heating liquid and convey it through orifice *o* to the heating chamber. A stationary feed pipe *t* for heating liquid discharges into this receptacle.

The top disc *h* is insulated, as, for example, by a layer of "bakelite" *u*, to prevent radiation of heat from the passage above it to the bowl space below it.

The heating chamber preferably carries radial wings or blades *v*, which facilitate rotation with the bowl of its contents.

It is not imperative that the heating chamber shall extend down to the bottom of the bowl. The dimensions of the heating chamber may be varied in accordance with variations in bowl structure and variations in material to be heated; although if it be arranged as shown in the drawings, it will be adapted to practically all materials by regulating the temperature and rate of flow of the heating liquid.

Surrounding the upper part of the bowl are the usual receiving pans down which the separated ingredients flow to spouts or troughs (not shown) leading to portable receiving vessels. In the present construction, there is a set of three pans, *x*, *y* and *z*, the top one being arranged to receive the lighter

separated ingredient, the middle one the heavier separated ingredient and the lower one the heating liquid discharged from the heating chamber. It will be observed that this heating liquid will discharge against the floor of the middle pan and therefore somewhat heat the separated heavier ingredient flowing down such floor, thereby still further increasing its fluidity and expediting its discharge through the spouts above mentioned.

Assume that a refrigerated mixture of oil and crystalline wax is fed through the feed tube *j* into the interior of the bowl and is thence distributed throughout the spaces, between the liner discs. Centrifugal force operates to throw the wax outwardly while the oil is displaced inwardly.

It is desirable, if not necessary, to delay admission of heating fluid (say hot water) to the heating chamber until after the bowl has been filled and the materials have been divided, by centrifugal force, into an outer zone of wax and an inner zone of oil. Heat exchange between the hot water and the cold wax melts that part of the wax nearest the wall of the heating chamber so as to render it sufficiently fluid to readily flow out of the bowl through the passage above and outside the top disc *h*, the fluidity of the wax being maintained in this passage by reason of the extension of the radiator thereinto. The oil will flow out through the passage within the neck of the top disc.

By the above means and method of heating the outer zone of the solidified or crystallized heavy ingredient, the temperature of such outer zone may be more easily regulated, the heat will penetrate to a more uniform depth, and the starting of the centrifugal operation is much easier, than if the hot liquid were introduced directly into the bowl space. The present invention also has the advantage that the heavier ingredient is discharged separately and therefore does not have to be subjected to any distilling or other dehydrating process.

If the invention is used in the separation of stearin from oleo, the mixture should be at a temperature of about ninety degrees F. in order to crystallize the stearin. The heating liquid, which may be water, should be at a temperature sufficient to melt the outer layer of stearin but of course not sufficient to melt the inner layer. Stearin melts at a temperature of 122 degrees F. The temperature of the water as it flows into the heating chamber should be about 150 degrees F.

In the case of wax distillates, the melting points of the various waxes vary from 100 degrees to 160 degrees F. The water should be hot enough to melt the wax having the highest melting point and should, therefore,

enter the heating chamber at from 160 degrees to 180 degrees F.

It is apparent that the invention is not limited in its application to the separation 5 of wax from mineral oil wax distillates, nor to the separation of stearin from oleo; these two substances of widely different characteristics being cited merely as examples of useful applications of the process.

10 It is clear that the process is applicable to the separation of any solid from a liquid when the solid is capable of being melted.

I am aware that the terms "solid" or "liquid" do not indicate absolute conditions, 15 but only relative conditions, and that there is an intermediate stage of semi-solidity or semi-liquidity. In speaking, however, of "solids" undergoing separation in the bowl, I mean to imply a condition that is not 20 free-flowing, as otherwise the use of my invention would be unnecessary.

It will be understood that while it is advisable, if not necessary, to maintain the 25 surface opposed to the bowl contents at a substantially constant temperature during any desired operation, it may be necessary, in certain processes, to provide one temperature for one operation and another temperature for another operation, which successive 30 operations may or may not take place without stoppage of the machine. By providing (for example) heating fluids of different temperatures, the surface of the radiator may be maintained at correspondingly different 35 predetermined temperatures.

Where, in the claims, I refer to a primary heating medium, I intend thereby to comprehend hot water (although not be limited thereto) and intend to exclude any intermediate 40 heat-transmitting medium such as the wall of the heating chamber contacting with the wax, stearin, or other solidified heavy ingredient. While such wall is heated, its function as an intermediate 45 heating medium or heat transmitter is incidental, its main function being to prevent the primary heating medium from mixing or otherwise contacting with the wax or stearin and to simplify the control of the 50 application of heat to the wax or stearin.

I do not herein claim any novel structural features herein described, as the same are claimed in an application filed by me March 25, 1922, Serial No. 546,810, of which 55 this application is a division.

Having now fully described my invention, what I claim and desire to protect by Letters Patent is:

1. The process of separating two ingredients of different specific gravities which 60 form a solution above a certain temperature and the heavier of which solidifies below such temperature but at a temperature higher than that at which the other in-

gradient solidifies, which comprises subjecting 65 the mixture to a temperature which will maintain the lighter ingredient liquid and the heavier ingredient solid, subjecting the mixture to centrifugation to divide the ingredients into zones, subjecting that part of 70 the heavier ingredient which during centrifugation is more remote from the lighter ingredient to the influence of a primary heating medium, regulating the temperature of said heating medium to produce heat 75 sufficient to liquefy the specified part of the heavier ingredient but insufficient to liquefy the part adjacent to the lighter ingredient, maintaining said heating medium out of 80 direct contact with the heavier ingredient, and separately flowing away from the locus of separation the lighter ingredient and the liquefied part of the heavier ingredient.

2. The process of separating two ingredients of different specific gravities which 85 form a solution above a certain temperature and the heavier of which solidifies below such temperature but at a temperature higher than that at which the other ingredient solidifies, which comprises subjecting 90 the mixture to a temperature which will maintain the lighter ingredient liquid and the heavier ingredient solid, subjecting the mixture to centrifugation to divide the ingredients into zones, subjecting that part 95 of the heavier ingredient which during centrifugation is more remote from the lighter ingredient to the influence of a primary heating medium, regulating the temperature of said heating medium to produce heat sufficient to liquefy the specified part of the heavier ingredient but insufficient to liquefy the part adjacent to the lighter ingredient, separately flowing away from the locus of separation and discharging 100 the lighter ingredient and the liquefied part of the heavier ingredient, subjecting the outflowing heavier ingredient to the influence of a primary heating medium in its passage from the locus of separation to the point of discharge, and maintaining said heating medium out of direct contact with the heavier ingredient while in the locus of separation and during its passage toward 105 the discharge.

3. The process of centrifugally separating two ingredients of different specific gravities which form a solution above a certain temperature and the heavier of which solidifies below such temperature but at a 110 temperature higher than that at which the other ingredient solidifies, a mixture of which has been subjected to a temperature which will maintain the lighter ingredient liquid and the heavier ingredient solid, which comprises subjecting the mixture to 115 centrifugation to divide the ingredients into zones, separately flowing away from the

locus of separation the lighter ingredient and the heavier ingredient, discharging the heavier ingredient from the centrifuge at a point distant from the locus of separation, subjecting the outflowing heavier ingredient to the influence of a primary heating medium in its passage from the locus of separation to the point of discharge and maintaining said heating medium out of direct contact with the heavier ingredient.

4. The process of centrifugally separating two ingredients of different specific gravities which form a solution above a certain temperature and the heavier of which solidifies below such temperature but at a temperature higher than that at which the other ingredient solidifies, a mixture of which has been subjected to a temperature which will maintain the lighter ingredient liquid and the heavier ingredient solid, which comprises subjecting the mixture to centrifugation to divide the ingredients into zones, separately flowing away from the locus of separation the lighter ingredient and the heavier ingredient, discharging the heavier ingredient from the centrifuge at a point distant from the locus of separation, heating the discharge passage while excluding admission thereto of a foreign liquid, and delivering the heavier ingredient from the centrifuge without admixture with a heated liquid from which it must be separated.

5. The process of separating two ingredients of different specific gravities one of which is in a liquid state and the other of which is solidified, which comprises subjecting the mixture to centrifugation to divide the ingredients into zones, subjecting that part of the solidified ingredient more remote from the liquid ingredient to the action of a flowing stream of fluid sufficiently hot to liquefy such part, maintaining the heating fluid out of contact with the part of the solid undergoing liquefaction, and flowing off separately the ingredient that has been so liquefied, the other ingredient that had not been solidified, and the heating fluid.

6. The process of separating two ingredients of different specific gravities one of which is in a liquid state and the other of which is solidified, which comprises subjecting the mixture to centrifugation to divide the ingredients into zones, flowing off separately the two ingredients, subjecting that part of the solidified ingredient more remote from the liquefied ingredient and in the locus of separation, and also the heavier ingredient in its passage to the discharge, to the action of a flowing stream of fluid sufficiently hot to liquefy such ingredient, and maintaining said heating fluid out of contact with such ingredient while the latter is in the locus of separation and during its discharge.

7. The process of separating two ingredients of different specific gravities one of which is in a liquid state and the other of which is solidified, which comprises subjecting the mixture to centrifugation to divide the ingredients into zones, flowing off separately the two ingredients, subjecting the heavier ingredient in its passage from the locus of separation to the point of discharge to the heating action of a flowing stream of fluid sufficiently hot to prevent clogging in the discharge passage, and maintaining the heating fluid out of contact with the heavier ingredient.

8. The process of separating a solution of mineral lubricating oil and wax which comprises subjecting such solution, in a substantially undiluted form, to a temperature that will solidify the wax and throw it out of solution, subjecting the mixture to centrifugal force to divide the ingredients into an outer zone of wax and an inner zone of oil, subjecting that part of the wax that during centrifugation is more remote from the oil to the influence of a primary heating medium, regulating the temperature of such heating medium to produce heat sufficient to liquefy the specified part of the wax but insufficient to liquefy the part of the wax adjacent to the oil, maintaining said heating medium out of contact with the wax, and separately flowing away from the locus of separation the oil and the liquefied part of the wax.

9. The process of separating a solution of mineral lubricating oil and wax which comprises subjecting such solution, in a substantially undiluted form, to a temperature that will solidify the wax and throw it out of solution, subjecting the mixture to centrifugal force to divide the ingredients into an outer zone of wax and an inner zone of oil, subjecting that part of the wax that during centrifugation is more remote from the oil to the influence of a primary heating medium, regulating the temperature of such heating medium to produce heat sufficient to liquefy the specified part of the wax but insufficient to liquefy the part of the wax adjacent to the oil, separately flowing away from the locus of separation and discharging the oil and the liquefied part of the wax, subjecting the outflowing liquefied wax to the influence of a primary heating medium in its passage from the locus of separation to the discharge, and maintaining said heating medium out of contact with the wax while in the locus of separation and during its passage toward the discharge.

10. The process of separating a solution of mineral lubricating oil and wax which comprises subjecting such solution, in a substantially undiluted form, to a temperature that will solidify the wax and throw it out of solution, subjecting the mixture to centrifu-

gal force to divide the ingredients into an outer zone of wax and an inner zone of oil, separately flowing away from the locus of separation the wax and oil, discharging the wax from the centrifuge at a point distant from the locus of separation, subjecting the outflowing wax to the influence of a primary heating medium in its passage from the locus of separation to the point of discharge and

maintaining said heating medium out of direct contact with the wax.

In testimony of which invention, I have hereunto set my hand, at New York, on this 31st day of July, 1923.

CYRUS HOWARD HAPGOOD.
